PRESSURE COOKER

Lawrence L. Ludington, Muncie, Ind., assignor to
 Ball Brothers Company, Muncie, Ind., a corporation of Indiana

Application May 23, 1935, Serial No. 23,031

3 Claims. (Cl. 220—57)

The object of my invention is to provide a sealing closure for pressure vessels, such as for instance, as pressure cookers, the construction being such as to be readily placed in pressure retaining association with a container and as readily removable therefrom, the mechanism being of such character that retraction of the clamping elements will automatically lift the closure from its seat.

10 Fig. 1 is a radial section showing the parts in closed position;

Fig. 2 a similar view showing the parts in cover-lifted position; and—

15 Fig. 3 a fragmentary plan of the mouth of the receptacle.

In the drawing, 10 indicates a container having a mouth 11 subtended by an annular cover seat 12.

The mouth of the receptacle is defined by a flange 10' perforated at spaced circumferential 20 intervals, as indicated at 13, and provided, at the root of each perforation 13, with a groove 14, parallel with the axis of the mouth, for a purpose which will appear.

The cover is a circular structure 20, preferably 25 a hollow casting, as indicated, provided with a seat 21 adapted to mate with seat 12.

Cover 20, at circumferentially spaced intervals corresponding to the spacing of perforations 13 and the grooves 14, is radially perforated at 22 30 and projected through each perforation is the tip 23 of a locking pin 24, said tip being adapted to enter and cooperate with a perforation 13.

Pins 24 are arranged radially in a circumferential series within the cover 20 and adjacent their 35 inner ends are transversely slotted as indicated at 25.

Rising axially from the lower wall of cover 20 is a pin 30 threaded at its upper end, as indicated at 31, said threaded end projecting upwardly 40 through the axial opening 33 through the upper wall of cover 20.

Threaded upon threads 31 is a thimble 35 provided with an outwardly extended circumferential flange 36 at its lower end, and sleeved over said 45 thimble and resting upon said flange is a bell 37 provided at its lower end with a circumferential flange 38 upon which the inner ends of pins 24 rest. Sleeved over bell 37 and resting thereon is a larger bell 39, the lower edge of which projects 50 into the several transverse slots 25 of pins 24, thereby retaining said pins between the two bells.

Sleeved over the upper part of thimble 35 is a sleeve 40 which rests upon bell 39 and which 55 is non-rotatively secured to thimble 35 by one or more suitable temper screws 41. Sleeve 40 is part

of a handle structure 42 by means of which thimble 35 may be rotated. Bells 37 and 39 may either rotate with thimble 35 and elements 40—42 or may remain non-rotative relative to pins 24.

When pins 24 are in their upper or released 5 positions, as shown in the full lines in Fig. 1, their ends project radially from the circumference of cover 20 and may be brought into registry with the several slots 13 by downward movement in grooves 14 until seat 21 rests upon seat 12, 10 whereupon the cover is turned through a short angle to bring the projecting ends of pins 24 beneath the upper walls 13' of perforations 13. Thereupon turning of the thimble 35 in appropriate direction depresses bells 37 and 39, consequently depressing the inner ends of pins 24, the said pins, near their outer ends fulcruming upon adjacent portions of the cover structure and engaging the upper walls 13' of perforations 13 to hold the cover structure in seated position upon 20 seat 12.

After a structure of this kind has been in operation for some time under pressure, there is a tendency of the cover to stick upon seat 12. Reverse rotation of thimble 35 operates, through 25 flange 38, to positively lift the inner ends of pins 24, whereupon the tips 23, at their lowermost portions, engage the lower walls 13'' of slots 13, as indicated in Fig. 2, and the pins engage abutments 20' of the cover 20 so that the cover is 30 positively lifted from its seat.

When the seat 21 has been forced from seat 12, the cover structure may be readily rotated to bring the projected ends 23 and pins 24 into alignment with the grooves 14, whereupon the 35 cover structure may be readily lifted from the container.

I claim as my invention:

1. The combination, with a container having an open mouth provided with a circumferential series of spaced pin pockets, of a cover structure provided with a circumferential series of radially projecting pins, the projected end of each of which is adapted to alternately engage the upper and lower walls of one of said pockets and the cover structure providing a radial guide for each pin with intermediate oppositely disposed fulcrums for the associated pin, a threaded axial post carried by said cover, and a handle structure threaded upon said post, said handle structure comprising a pair of elements between which the inner ends of said pins are projected. 40 45 50

2. The combination, with a container having an open mouth provided with a circumferential series of spaced pin pockets, of a cover structure 55

provided with a circumferential series of radially projecting pins, the projected end of each of which is adapted to alternately engage the upper and lower walls of one of said pockets and the 5 cover structure providing a radial guide for each pin with intermediate oppositely disposed fulcrums for the associated pin, a threaded axial post carried by said cover, and a handle structure threaded upon said post, said handle structure comprising means for positively engaging the inner 10 ends of the pins, whereby the handle structure may shift said inner ends axially of the cover structure in opposite directions.

3. The combination, with a container having 15 an open mouth provided with a circumferential series of spaced pin pockets, of a cover structure provided with a circumferential series of radially

projecting pins, the projected end of each of which is adapted to alternately engage the upper and lower walls of one of said pockets and the cover structure providing a radial guide for each pin with intermediate oppositely disposed fulcrums for the associated pin, a threaded axial post carried by said cover, and a handle structure threaded upon said post, said handle structure comprising an internally threaded sleeve, a main body telescoped over said sleeve, a connection integrating said sleeve and main body, a pair of bells interposed between said sleeve and main body, one underlying the inner ends of all of the pins and the other overlying said inner ends in transverse slots in said pins. 10 15

LAWRENCE L. LUDINGTON.
